(57) **CLAIM**

We claim the ornamental design for a comb with integrated liquid dispenser, as shown and described.

DESCRIPTION

FIG. 1 is a front view of the comb with integrated liquid dispenser.

FIG. 2 is a back view of the claimed design.

FIG. 3 is a left side view of the claimed design.

FIG. 4 is a right side view of the claimed design.

FIG. 5 is a top view of the claimed design.

FIG. 6 is a bottom view of the claimed design; and,

FIG. 7 is a perspective view of the claimed design.

The broken lines shown in FIG. 2 depict portions of the comb with integrated liquid dispenser that form no part of the claimed design.
